[57] CLAIM

The ornamental design for a telephone set, as shown.

DESCRIPTION

FIGS. 1 and 2 are respectively top and bottom plan views in cradled relationship of a telephone set showing my new design;

FIGS. 3 and 4 are respectively right and left side elevational views thereof;

FIGS. 5 and 6 are respectively front and rear elevational views thereof, and

FIG. 7 is a left side, top and front perspective view thereof in cradled relationship; and

FIGS. 8 is a left side, top and front perspective view of the base of the telephone set, and an underneath perspective view of the handset positioned above the base in bracketed relationship.

FIG. 1

FIG. 2

FIG. 3
